UNITED STATES PATENT OFFICE.

HOWARD ARMSTRONG, OF LESTERSHIRE, NEW YORK.

MACHINE FOR MANUFACTURE OF COMPOSITION BOARDS.

1,189,650.

Specification of Letters Patent.

Patented July 4, 1916.

Application filed March 27, 1912. Serial No. 686,648.

To all whom it may concern:

Be it known that I, HOWARD ARMSTRONG, of Lestershire, in the county of Broome and State of New York, have invented certain 5 new and useful Improvements in Machines for Manufacture of Composition Boards; and I hereby declare that the following is a full, clear, and exact description thereof, reference being had to the accompanying 10 drawings, which form part of this specification.

This invention is an improvement in machines for manufacturing composition boards such as are commonly known as 15 leather-board, fiber-board, binder-board, press-board, and the like. Such machines, generally speaking, comprise means for felting or matting the stock, usually consisting of a belt upon which the wet stock is laid and 20 upon which it is carried past means for extracting the moisture from the stock to a roll upon which the felt layer is wound and compressed until a sufficient amount has accumulated upon the roller to form a board 25 of the desired thickness; then the compressed material on the press roll is removed. In order to do this it is necessary to first split or 30 cut the cylinder of material accumulated on the roll after which such material can be removed from the roll in the form of a sheet for further treatment.

The object of the present invention is to provide an efficient accurate and simple 35 means for cutting or dividing the material on the roll prior to its removal therefrom, and by which tearing or rupturing of the edges of the sheet adjacent the cut will be prevented thereby enabling the entire cylinder or sheet accumulated upon the roll to 40 be utilized. I am aware that heretofore various attempts have been made to cut such sheets from the press roll by interiorly arranged knives, and by reciprocating cutters; but the present invention is different 45 from all prior devices, and I will explain same in detail with reference to the accompanying drawings in which—

Figure 1 is a detail front elevation of part 50 of a machine showing the press roll and also the novel cutting devices, adapted to co-operate therewith, in inactive position. Fig. 2 is a detail view showing the clutch engaged. Fig. 3 is a detail transverse sectional view showing the operation of the parts in 55 cutting the material on the roll.

Referring to the drawings, 1 designates

the press roll of a Fourdrinier or other suitable paper making, or felting machine; and 2 designates a belt by which the felt layer is brought forward to the roll 1; the present invention however has nothing to do with the particular construction and operation of the means for felting the pulp.

When the machine is in operation the moist felt layer contacting with the surface 60 of the roll 1 adheres thereto and is wound around same under pressure against roll 2^b until a sufficient quantity of the felt has collected upon the roll 1 to form a cylinder or board of the desired thickness; the felt being 65 compressed during its collection on roll 1 by the operation of the co-acting roll 2^b indicated in Fig. 1. The rolls 1 and 2^b have their shafts journaled in suitable bearings in 70 the frame work of the machine as usual.

Mounted upon the frame adjacent the bearings of the roll 1 are bearings 4^a for a shaft 4 carrying a cutter blade 4^b; which blade may be secured to shaft 4 in any suitable manner, and preferably projects from the shaft 4 such a distance as 75 will insure the edge of the blade contacting with a bar 1^b, which may be of wood, fiber or rubber, set into a longitudinal groove 1^c in the periphery of the roll 1, the outer edge of bar 1^b being flush with and forming a continuation of the outer periphery of the roll 1.

One end of shaft 4 projects beyond its bearings, and upon this projecting end is 80 loosely mounted a gear 5 which meshes with a corresponding gear 1^e on the adjacent end of the shaft of roll 1. The gear 5 has on its outer face a clutch member 5^a which is adapted to be engaged by an opposed clutch member 6^a on a sleeve 6 splined on the end of shaft 4 beside the gear 5, as indicated in 85 the drawings. This sleeve 6 with its clutch member may be moved to or from the gear 5, so as to engage or disengage the clutch 90 members, by means of a hand lever 7 which is provided with pins 7^a engaging a groove 95 in the sleeve 6. Preferably the clutch members have only one interlocking tooth and notch, so that they will always engage at 100 the proper point.

A counterpoise may be attached to the outer end of the spindle of shaft 4 adjacent the clutch member 6, to keep the knife out of the way of the material being accumulated on the press roll except when the press roll is to be used. Said counterpoise pref-

erably consists of a pulley 8 having a weighted portion 8^a at one side, and so fixed to the shaft 4 that when the clutch is disengaged this weight will normally return 5 and hold shaft 4 in position with the knife 4^b uppermost or farthest away from the press roll as indicated in Fig. 1.

The gears 5 and 1^c are preferably of the same diameter and the parts should be so 10 proportioned that when the gear 5 is locked to the shaft 4, by means of the clutch, the knife will be rotated in unison with the roll and the knife edge will always meet or register with the bar 1^b on the press roll.

15 The press roll may be made of iron, wood or faced with any suitable material. The position of the knife in the knife bar may be regulated by screws or bolts 1^a to hold it in place in the slot in the roll.

20 Operation: When the machine is in operation the front of the press roll revolves in an upward direction, and when the clutch is thrown in, the forward part of the knife roll moves in a downward direction, as indicated 25 by the arrows in Fig. 3. The operator stands beside or in front of the press roll and when a sufficient amount of material has accumulated thereupon he throws the clutch into gear, by shifting lever 7, there- 30 by causing the shaft 4 to rotate; and as it revolves the knife 4^b contacts with the ma- terial on the roll and cuts through the latter until its edge strikes against the bar 1^b thus 35 making a clean cut through the material on the roll lengthwise of the roll; then the operator throws the clutch out of gear and re- 40 moves the severed board from the roll 1. The weight or counterpoise turns shaft 4 automatically until the knife is out of posi- 45 tion to contact with the material being ac- cumulated thereupon.

I do not consider the invention restricted to the particular mode of attaching the knife to the bar nor to the particular kind of clutch shown, nor to a manually controlled clutch; the particular improvement or essential feature of the invention being the provision of a normally inoperative knife located outside of the path of the

material and beside the press roll, which 50 at the desired time can be caused to revolve at the speed of the press roll and sever the material thereon.

What I claim is:

1. In a machine of the character de- 55 scribed, the combination of a press roll, a normally idle shaft journaled beside the press roll, a knife carried by said shaft, a loose gear on said shaft, a gear on the press roll shaft meshing therewith, and a clutch 60 on the knife shaft whereby said shaft may be locked to the gear thereon when it is desired to cause the knife to sever the mate- rial on the press roll.

2. In a machine of the character de- 65 scribed, the combination of a press roll, a normally idle shaft journaled beside the press roll, a knife carried by said shaft, a loose gear on said shaft and a gear on the press roll meshing therewith, and a clutch 70 whereby the knife shaft may be locked to or disengaged from the gear thereon to cause the knife to sever the material on the press roll; with means for normally holding the knife shaft in such position that the 75 knife will not contact with the material on the press roll, substantially as described.

3. In a machine of the character de- 80 scribed, the combination of a press roll, a shaft journaled beside the press roll, a knife 85 carried by said shaft, a gear loose on said knife shaft, gearing for driving said loose gear from the press roll, and a manually operable clutch whereby the knife shaft may be locked to or disengaged from the gear thereon to cause the knife to sever the material on the press roll; with a weight at- 90 tached to said shaft adapted to normally hold the knife shaft in position to keep the knife out of contact with the material on the felt roll.

In testimony that I claim the foregoing as my own, I affix my signature in presence of two witnesses.

HOWARD ARMSTRONG.
